UNITED STATES PATENT OFFICE.

ZENON KLOSOWSKI, OF WARSAW, POLAND.

PRESS PLATE FOR RAIL FISHPLATES.

Application filed September 24, 1925, Serial No. 58,423, and in Germany December 9, 1924.

This invention relates to press plates for rail fishplates and has for its principal object the provision of means as an auxiliary to the ordinary fishplate for pressing the intermediate portions of the latter into intimate contact with the rail-web at the rail joins whereby the relative vertical play of the rail ends under load of passing traffic is inhibited.

10 Other objects of the invention find their realization in the novel construction of press plate illustrated in the accompanying drawing and described in the following specification and claim.

15 In the drawings in which the same reference characters are applied to similar parts, Fig. 1 shows a side elevational view of my improved press plate.

20 Fig. 2 is a side elevation of adjacent rail ends with their appurtenant fishplates including the press plates of the present invention.

Fig. 3 is a plan view of the same.

25 Fig. 4 is a cross sectional view taken in the plane of the rail joint.

Referring now in detail to the several figures,—

The pressplate A is formed on that side which bears against the fishplate with a 30 surface slightly curved lengthwise presenting its convex side toward the fishplate. On the other side the pressplate is reinforced by a rib *a* and has two oblong holes *b'* corresponding with the fishplate holes.

35 The pressplates A are mounted on fishplates one on each side of the rail and are fastened tightly by means of two bolts *b* going right through the web of the rail, both fishplates, and the pressplates as shown in

Figs. 1, 2, 3. The fishplates (c), owing to the 40 slightly curved surface of the pressplates are pressed tightly against the web surfaces of the rail at the rail joint and are thereby held rigidly in place.

The pressure exercised upon the fishplate 45 (c) at the rail joint (S) absorbs the vertical play of rail ends caused by the variation of loads, thus softening to a great extent and even eliminating altogether the shock which is so harmful to the railway 50 rolling stock and the upper part of the cross tie, without influencing the capability of rails to expand or contract longitudinally owing to changes of temperature.

I claim:

55 In a rail joint construction which includes fish plates crossing the joint between the rail ends, a rigid press plate having a convex side pressing against one of the fish plates adjacent the joint between the rail ends, and having apertured ends out of contact with said fish plate in the initial position of said press plate when the convex portion thereof is in untensioned contact with said fish plate, the apertures in said ends being 60 in registry with existing bolt holes in said fish plate, the bearing point of said press-plate being adapted to be drawn into active pressure against said fish plate by bolts passing through registering apertures in said 65 fish plates and press plates, for slightly flexing the fish plate rail-ward at the middle, maintaining the intermediate part of said fish plate in forcible contact with the edges of the rail webs at the rail ends.

70 In testimony whereof I have affixed my signature.

ZENON KLOSOWSKI.
